UNITED STATES PATENT OFFICE.

MAX GÜTTNER, OF CHEMNITZ, AND RICHARD BAEGER, OF EHRENBERG, GERMANY.

CENTRIFUGAL MACHINE.

SPECIFICATION forming part of Letters Patent No. 730,114, dated June 2, 1903.

Application filed August 7, 1902. Serial No. 118,784. (No model.)

To all whom it may concern:

Be it known that we, MAX GÜTTNER, residing and having post-office address at Limbacherstrasse 41, Chemnitz, Saxony, Germany, and RICHARD BAEGER, residing and having post-office address at Ehrenberg, near Altenburg, Germany, subjects of the German Emperor, have invented certain new and useful Improvements in Centrifugal Separators, of which the following is a specification.

This invention relates to an apparatus for separating liquids from solid matter. It possesses over all former devices of this kind the advantage that it may be used for separating the solid matter from street-sewage, fecal substances, rinsing-water of closets, and similar materials which on account of their composition impede the separation of the solid parts from the liquid matter, because the watery parts contained in these matters stick extraordinarily fast to the solid ingredients impermeable to water. Mash in manufacturing beer also belongs to the above-mentioned mixtures of matter, it being well known that it has to be cleared by means of a lengthy process. The present apparatus renders it possible to shorten this refining process or to separate the clearing-wort from the draff in a very short time.

In the accompanying drawings, Figure 1 is a vertical longitudinal section of the apparatus, while Fig. 2 represents a plan view and partial transverse section thereof.

Around the vertical main shaft 1 a number of separating-baskets revolve and at the same time revolve on their own axes, said baskets being journaled on the main shaft 1 in a suitable and well-known manner and consisting of imperforate metallic sheets. These baskets 2 have a truncated conical form, the narrower part of which is disposed upward, and each comprises a lower chamber 4, separated from an upper chamber by means of a horizontal annular disk 3 in such a manner that the lower annular chamber 4 communicates with the upper chamber by a slot 5, passing around the conical wall. The chamber above the annular disk 3 is divided into several parts by means of perforated plates 6, arranged and attached in a radial direction and extending inwardly to the edge of the

annular disk 3 and upwardly to the inwardly and outwardly turned flange 7 of the basket. A supply-pipe 9 leads from a distributing-drum 8, centrally arranged over the main shaft 1, into the separating-baskets 2 and terminates at its lower end in the lower chamber 4 of the separating-basket. The parts 8 and 9 partake of the revolving motion of the main shaft 1, and the separating-baskets 2 rotate with them and also around the pipes 9. Each pipe 9 rests upon peculiarly-formed catching-plate 10, built within the separating-basket 2. This catching-plate is inclined, has the shape of a trough, and is rigidly attached at one side to the cast-iron revolving disk 12, Fig. 1, by means of a horizontal flange 11, Fig. 2, and its other side has a downwardly-elongated mantle part 13, which projects through the opening 14 of the revolving disk 12. One of the edges 15 of the catching-plate 10 is extended and arranged vertically, and consequently parallel, to the axis of the separating-drum.

In Fig. 2 the four separating-baskets are singly represented, so that the catching-plates may be distinctly seen. *a* represents a top view of the separating-basket and catching-plate. In *b* the catching-plate is removed, while the separating-basket is represented in complete exterior view. The opening 14 in revolving disk 12 at the bottom of the basket is visible. At *c* the catching-plate is shown alone, the separating-basket being completely removed. Particular attention is called to the attachment of the catching-plate to the revolving disk by means of the borders 11 and 11', which are fastened by rivets or screwed and which on account of the narrow space available are turned outwardly on one side and inwardly on the other. In *d* both the separating-basket and the catching-plate is shown in horizontal section. The walls 6 of the scoop-chambers are perforated or consist of wirework. The separating-baskets are journaled in such a manner that crowns of balls 17 are built within the bottom revolving disk 12 and the covering-disk 16, so that the separating-baskets can accomplish a planetary movement with very little friction.

On the upper revolving disk 16 funnel-like discharges 18 are arranged, one adjacent to

each of the four separating-baskets 18, as seen in Fig. 1 and in Fig. 2 at *b*. These funnels 18 discharge into a chamber built within the fixed frame of the machine, said chamber being closed by the horizontal cover 19 and comprising cylindrical outer wall-plate 20 and a bottom 21, which is sloped from its highest point at 21, Fig. 1, downwardly to the discharge-pipe 22, where the separated liquid 10 passing from the funnel 18 finds outlet.

The system rigidly attached to the main shaft 1 is driven in a well-known manner by means of a belt running upon the pulley 23, while the following mechanism, which has 15 been built for the particular purpose of the present invention, brings about the radiation of the separating-baskets.

On the under side of the pulley 23 a leather ring 24, extending laterally from said pulley, 20 is provided and communicates motion to friction-cone 25, formed also of leather disks, through the convex friction-wheel 26. The convex disk 26 rotates around an axis, (indicated by the dashed and dotted line 27,) and 25 a spring 28, arranged in the same direction of axis, presses the convex disk against both leather cones 24 25. To vary the speed of rotation of the cone 25, the axis of rotation 27 of the convex friction-wheel is moved around 30 the center 30 to any position by means of the hand-lever 29. When the lever 29 is in the position shown in Fig. 1, the cones 24 and 25 have nearly the same circumferential speed. If the lever 29 is lowered, so as to stand horizontal, the two radii of the convex friction-wheel which decide the speeds of rotation of the cones 24 and 25 will change considerably, and the circumferential speed of 25 will then be smaller than that of 26. If the lever 29 is 35 further lowered until the axis 27 of the convex friction-wheel 26 is in line with the friction-cone 25, the latter will stand still. Thus according to the proportions of size of the two friction-cones 24 and 25 and according to the 40 adjusted position of the lever 29 it is possible to give the shaft 31 any desired number of revolutions from zero to a maximum value. A pinion 32, attached to the vertical shaft 31, drives a spur-wheel 33, Fig. 1, which carries 45 a worm 34, Fig. 2, meshing with the two worm-wheels 35. These latter again are keyed with the worm-wheels 36, which have the same axis and in turn mesh with the worm-wheels 37, and these, 37, are arranged on the 50 same axis with the pinions 38, Fig. 2, which mesh with the spur-gears 39, fixed to the separating-baskets 2. It is obvious, therefore, that the rotary motion received at 23 is transmitted through the medium of the movable 55 convex friction-wheel gearing to the separating-baskets 2.

The central frame for the shaft-bearing of the shafts 1 and 31 is surrounded by an inclined sliding surface 40, which is encircled 60 at its upper part by the fixed cylindrical formed plate 41.

The operation of the invention is as follows:

The raw material is to be separated. For instance, the mash in brewing beer is conducted to the distributing-drum 8 in a stream through 70 the central opening 42 in the cover 19 and passes farther along through the distributing-pipes 9 into the lower annular chamber 4 of the separating-baskets 2. While the system rotates quickly about the main shaft 1, the 75 lever 29 is adjusted so that the separating-baskets 2 do not immediately begin to revolve around their own axes. The mash supplied at 4 is blocked in the separating-baskets under 80 the influence of the centrifugal force at the zone of each separating-basket which is farthest distant from the shaft 1. At the separating-baskets *d* in Fig. 2 this quantity of liquid is indicated by shade-lines. According to the laws of hydrostatics the liquid will 85 acquire a cylindrical surface, the vertical axis of which lies parallel to the shaft 1. When the liquid has risen in the single separating-baskets so far as indicated at *d* in Fig. 2, it will commence to flow over at the edge 7, Fig. 90 1, and spout out through the funnel 18. At this moment the planetary movement of the separating-baskets is to be set in action by means of the lever 29. In the meantime the operation progresses. Under the influence of 95 the centrifugal force the heavier ingredients of the mash, the draff and starch flour, settle down at the circumference of the separating-basket. Fresh mash is continually supplied through 9 and let through the annular slits 5 100 in the baskets, while the cleared wort passes over the edge 7 in a continuous stream to the funnel 18. As the rotation of the separating-basket 2 progresses the draff thrown out is gradually led around and approaches the 105 lower vertical edge 15 of the catching-plate 10, so that it finally slips down from the sieve-wall 6 on account of the centrifugal force (see Fig 2) at *d* and passes into the interior of the catching-plate 10. On this journey 110 the draff is nearly completely released of liquid constituents as these find occasion of returning through the perforations of the cell-wall 6 to the liquid left back. As mentioned above, a scooping process in the real meaning of the word takes place here. Should the 115 openings of the sieve-surface in 6 be choked during this operation, this would not be a disadvantage, because the few liquid constituents which are perhaps drawn along find occasion to flow back from the single scooping-chambers through the slot-openings 5 into the annular space 4 and walls, pass on to that point situated at the greatest distance from the shaft 1, joining again the new material to be separated which comes from the pipe 9. The conical form of the separating-basket casing 2 considerably assists the operation described.

In consequence of the new material to be 130 separated passing through slot 5 a certain disturbance or stream is produced in the material exposed to the separating process, and it is obvious that this agitation of the liquid

will be mostly conspicuous near the slot 5, and the more the liquid approaches the edge 7 the less agitated the stream will be, so that the brightness of the cleared wort flowing 5 over at 7 cannot be influenced.

The draft expelled from the scooping-chambers runs down the sloped catching-plate 10 toward the opening 14 at the bottom and gets from here to the circumference of the 10 casing 41 or onto the inclined plane 40 and is removed at foot of the machine.

Having now fully described our invention, we declare that what we claim is—

1. In a centrifugal separator for continually separating mixed liquid and solid constituents, the combination of a revoluble drum, a plurality of revoluble separating-baskets arranged within and revoluble in said drum, means for driving said drum and separating-baskets and means for varying the speed of both, of perforated plates vertically arranged within each separating-basket and forming chambers or spaces therein and means for leading raw material to be separated into the separating-baskets, substantially as described. 15
2. In a centrifugal separator for continually separating mixed liquid and solid constituents, the combination with a revoluble drum, a plurality of revoluble separating-baskets arranged within and revoluble in said drums, and divided into upper and lower communicating chambers, means for driving said drum and separating-baskets, and means for varying the speed of both, of perforated plates vertically arranged within each separating-basket, a distributing-drum arranged around the vertical axis of the separator, distributing-pipes leading from said drum into the lower chambers of said separating-baskets, and a discharge-pipe for conducting the separated material to its place of consumption, substantially as described. 30
3. In a centrifugal separator for continually separating mixed liquid and solid constituents, the combination with a revoluble disk, revoluble separating-baskets arranged upon the disk and divided into upper and lower communicating chambers, means for driving said disk and separating-baskets, and means for varying the speed of both, of perforated plates vertically arranged within each separating-basket and forming chambers or spaces therein, a distributing-drum arranged 35 around the vertical axes of the separator, a distributing-pipe leading from the drum into the lower chamber of said separating-baskets, catching-plates attached to a revolving disk, a chamber having a sloping bottom, surrounding the baskets, a discharge-pipe for conducting the separated material from the separating-baskets into the said chamber, and a second discharge-pipe in the chamber for conducting the separated material from said 60 chamber to its place of consumption, substantially as described. 45
4. In a centrifugal separator for continually separating mixed liquid and solid constituents, the combination with the revoluble drum having a vertical shaft, and revoluble 70 separating-baskets arranged within the drum, of a pulley for driving the centrifugal system attached to the vertical shaft, a conical friction-ring arranged on said shaft, below the driving-pulley, a shaft parallel with the main shaft, a second conical friction-ring arranged on the shaft parallel to the main shaft of a spring-pressed convex friction-wheel for communicating motion from the first friction-ring to the second ring, a lever for moving 80 the axis of the convex friction-wheel around a fulcrum-point, and means of transmitting the movement of the latter friction-ring to the separating-baskets. 75
5. In a centrifugal separator for continually separating mixed liquid and solid constituents, the combination with the revoluble drum having a vertical shaft, and revoluble separating-baskets arranged within the drum, of a pulley for driving the centrifugal 90 system, attached to the vertical shaft, a conical friction-ring arranged on said shaft, below the driving-pulley, a shaft parallel with the main shaft, a second conical friction-ring arranged on the shaft parallel to the main shaft, of a spring-pressed convex friction-wheel for communicating motion from the first friction-ring to the second ring, a lever for moving the axis of the convex friction-wheel around a fulcrum-point, means of transmitting the movement of the latter friction-ring to the separating-baskets, of perforated plates vertically arranged within each separating-basket, a distributing-drum arranged 100 around the vertical main shaft of the centrifugal separator, a distributing-pipe leading to the said separating-baskets, and a discharge-pipe for conducting the separated material to its place of consumption, substantially as described. 105
6. In a centrifugal machine, the combination with a plurality of separating-baskets revoluble together around a common axis, and each basket being also revoluble around its own axis, of radially-arranged partitions 110 within the separating-baskets. 115
7. In a centrifugal machine, the combination with a plurality of imperforate separating-baskets revoluble together around a common axis, and each basket being also revoluble around its own axis, of radially-arranged partitions within the separating-baskets. 120
8. In a centrifugal machine, the combination with a plurality of imperforate separating-baskets revoluble together around a common axis, and each basket being also revoluble around its own axis, of perforated radially-arranged partitions within the separating-baskets. 125
9. In a centrifugal machine, the combination with a plurality of imperforate separating-baskets revoluble together around a common axis, and each basket being also revoluble around its own axis, of imperforate radially-arranged partitions within the separating-baskets. 130

mon axis, and each around its own axis, of vertically-arranged partitions within the separating-baskets.

10. In a centrifugal machine, the combination with a plurality of separating-baskets revoluble around a common axis, each of said baskets having openings closed at their fronts but open toward the common axis, of means for carrying solid matter toward the common axis so that the said solid matter is thrown through the openings.

11. In a centrifugal machine, the combination with a plurality of separating-baskets revoluble around a common axis, and each basket being also revoluble around its own axis, of means in each basket for conveying solid matter to that side of the axis of each basket nearest the common axis of all the baskets.

2c 12. In a centrifugal machine, the combination with a plurality of separating-baskets revoluble around a common axis, and each basket being also revoluble around its own axis and having an opening closed at its front but open toward the common axis, of means in each basket for conveying solid matter to

that side of the axis of each basket nearest the common axis of all the baskets, so that the same may be thrown by centrifugal force through the opening.

13. In a centrifugal machine, the combination with a plurality of separating-baskets revoluble around a common axis, and each basket being also revoluble around its own axis, and provided with an opening closed at its front but open toward the common axis, and a discharge at its top, an annular disk dividing each of said baskets into an upper and a lower chamber, and provided with a slot to form a communication between them; 35 radial perforated plates secured to the walls of the upper chamber, and means for delivering the matter to be separated into the lower chamber.

The foregoing specification signed at Chem- 45 nitz this 24th day of July, 1902.

MAX GÜTTNER.
RICHARD BAEGER.

In presence of—

MORRIS LIPPMAN,
H. THIELE.
